RANGE AND CABINET CART

James A. Nelson, Elmhurst, George W. Kamin, Lombard, and Lawrence E. Wolske, Chicago, Ill., assignors to Cribben and Sexton Company, Chicago, Ill., a corporation of Illinois

Application March 30, 1950, Serial No. 152,922

4 Claims. (Cl. 126—39)

1

This invention relates to a range and cabinet cart. The invention is particularly useful with a range equipped with gas burners or electric heating elements, and in which a mobile cart provides a cabinet and table top structure in heat utilizing relation with the burners.

An object of the invention is to provide a range and cabinet part combination in which the cabinet is employed as part of the range under certain circumstances while providing a table in heat-receiving relation with the burners of the range. Other specific objects and advantages will appear as the specification proceeds.

The invention is shown in illustrative embodiments, by the accompanying drawings, in which—

Fig. 1 is a perspective view of a range embodying our invention; Fig. 2, a view similar to Fig. 1 but showing the cabinet cart portion of the range drawn forwardly on its rollers; Fig. 3, a front view in elevation of the range with the cart cabinet removed; and Fig. 4, a side view in elevation of the range as illustrated in Fig. 1.

In the illustration given in Figs. 1 to 4, inclusive, 10 designates generally a range frame. The frame provides at the bottom a compartment 11 which preferably is employed as a broiler compartment. Above the compartment 11, the frame provides an oven compartment 12. It will be understood that other types of heating compartments may be formed. In the specific structure given, the compartment closures are provided with handles 13 and 14 respectively. It will be understood that a burner or heating element (not shown) will be provided on the interior of one or both of the compartments.

Above the frame 10 and oven compartment 12 is a range top 15 which not only extends over the oven 12 but also extends laterally thereof so as to provide a projecting portion 16. A side wall 16^a and rear wall 16^b may be provided below the projecting portion 16 to form an enclosure for the space below. Burners 17 are provided over the projecting portion 16 of the range top as well as upon the portion thereof over the oven 12. The burners may be of any suitable type or construction. Operating knobs 18 may be provided along the front of range top 15 for opening and closing the gas lines leading to the burners and for regulating the temperatures, etc. The range top 15 may be provided with a back splash 19 of any suitable type or construction.

The cabinet cart 20 is preferably equipped with rollers 21 and is adapted to be received snugly within the space below the projecting range top portion 16, as shown more clearly in Figs. 1 and 2.

2

The cabinet provides a table top 22 just immediately below the portion of the burner top 16 and below the burners 17 carried thereby.

We prefer to provide the cabinet 20 with compartments having side openings 23, as shown more clearly in Fig. 2, so that when the cabinet is drawn forwardly there is provided access into the compartments of the cabinet directly from the side adjacent the oven and broiler compartments. We also prefer to provide the cabinet with 10 drawers 24 which open from the side already described. The cabinet may be provided with wiring connections and, for example, with a socket 25 to which a waffle iron, toaster, or other electrical cooking device may be connected. The 15 front portion of the cabinet 20 may also be provided with handles 26 similar in appearance to the handles 14 and which give the range and cabinet when combined, as shown in Fig. 1, a symmetrical or unitary appearance.

20

Operation

In operation of the structure shown in Figs. 1 to 4, inclusive the cabinet part is preferably kept within the space below the burner top projection 16 to form a closure for the opening, as illustrated in Figs. 1 and 4. In this position, the table top 22 is maintained below the burners 17 so that a warm top is provided for receiving heated dishes, platters, etc. when the cabinet is moved 30 outwardly to the position shown in Fig. 2. Similarly, the heat from the compartments 11 and 12 is utilized in keeping warm the dishes, etc. within the compartments of the cabinet. The cabinet may be moved with the warmed dishes 35 and the food carried by the table top thereof into the dining room or to any other desired point. If desired, it may be maintained in a dining room or breakfast room as a service table and cabinet. Toasters, waffle irons, and other cooking 40 apparatus may be used upon the table top 22. Used dishes may be returned in the cabinet and on the table top thereof to the kitchen sink or range.

As shown there is provided a unified appearance in the use of the cart and range in that the two provide a complete range. In addition, the cart is useful for storage of portable kitchen appliances and hand accessories of all kinds. The design is practicable when applying a right or 45 left hand oven. The cart is useful as a completely portable and integrated electric plug-in work center or, in other words, as a completely separate appliance. If desired, the cart may not be employed as a cart, but used rather as a distinct 50 part of the range, supported either on the floor or

in the range structure wherein it may be pulled out to its intermediate position but not detached from the range. In other words, the cart may be employed solely as a work shelf and cabinet portion of the range.

While in the foregoing specification we have set out a specific structure in considerable detail for the purpose of illustrating specific embodiments of the invention, it will be understood that such details of structure may be varied widely by those skilled in the art without departing from the spirit of our invention.

We claim:

1. In a range, a frame, vertically-disposed broiler and oven compartments supported by said frame, a range top over said oven compartment and having a portion extending laterally thereof, burners mounted in said last-mentioned portion of the range top, and a cabinet cart equipped with rollers and movable into and out of the space below said laterally-extending portion of said range top, said space being open only at the front thereof, said cabinet having a front wall adapted to close said space when said cabinet is in place within said space, a table top below said burners, and compartments below said top and opening laterally towards said oven compartment whereby said cabinet compartments receive radiant heat from said oven compartments.

2. In a range, a rectangular frame providing a rear wall and two side walls, vertically-disposed broiler and oven compartments supported by said frame adjacent one side wall thereof and terminating at a spaced distance from the other side wall thereof to provide an open space within said frame accessible from the front thereof, a range top mounted over said oven compartments and having a portion extending laterally thereof over said open space, burners mounted in said last-mentioned portion of the range top, and a cabinet cart equipped with rollers and movable into and out of the space below said laterally-extending portion of said range top, said cart having a side wall adjacent the side wall of said frame, a rear wall adjacent the rear wall of said frame, and a front wall adapted to close said space when said cart is within said space, said cart also having compartments therein adapted to receive containers of food and opening laterally toward said oven compartments, whereby said cabinet compartments receive radiant heat from said oven compartments and there-

by said containers of food within said compartments can be kept warm.

3. In a range, a frame, vertically-disposed broiler and oven compartments supported by said frame, a range top over said oven compartment and having a portion extending laterally thereof, walls enclosing the rear and side of the space below said laterally-extending range top portion and providing a compartment open only at the front thereof, and a cabinet equipped with rollers and movable into and out of the space below said laterally-extending portion of said range top, whereby radiant heat is received from said oven compartment upon said cabinet, said cabinet having a front wall adapted to close said space when said cabinet is drawn into said space.

4. In a range, a rectangular frame providing a rear wall and two side walls, vertically-disposed broiler and oven compartments supported by said frame adjacent one side thereof and terminating at a spaced distance from the other side wall thereof to provide an open space within said frame accessible from the front thereof, a range top mounted over said oven compartment and having a portion extending laterally thereof over said open space, means for heating said broiler and oven compartments, a cabinet equipped with rollers and movable into and out of the space below said laterally-extending portion of said range top, said cart having a side wall adjacent the side wall of said frame, a rear wall adjacent the rear wall of said frame, and a front wall adapted to close said space when said cabinet is drawn within said space, whereby said cabinet receives radiant heat within said space adjacent said oven when said space is thus substantially closed.
